UNITED STATES PATENT OFFICE.

JOSEPH O. LUTHY, OF SAN ANTONIO, TEXAS.

CELL-TESTER.

1,202,078.

Specification of Letters Patent. Patented Oct. 24, 1916.

Application filed February 26, 1913. Serial No. 750,859.

To all whom it may concern:

Be it known that I, JOSEPH O. LUTHY, a citizen of the Republic of Switzerland, residing at San Antonio, in the county of Bexar, State of Texas, have invented certain new and useful Improvements in Cell-Testers; and I do hereby declare the following to be a full, clear, and exact description of the invention, such as will enable others skilled in the art to which it appertains to make and use the same.

The invention relates to a simple and efficient portable device for testing battery cells and the like in order to indicate whether the cells are delivering the normal amount of current, or in other words, whether the voltage of the cells has or has not dropped below a predetermined minimum.

20 In its preferred form, the invention comprises a small closed casing containing an electro-magnet having a movable armature associated with a manually set indicating element, the magnet being wound to respond 25 to current of a given minimum voltage to attract the armature and thereby cause the indicating element to operate through an opening in the casing, the element preferably being so constructed and arranged that 30 upon the actuation of the armature and the visual indicating element, the circuit through the apparatus will be broken, thereby preventing unnecessary waste of the battery current, after which the parts may 35 be reset by hand for a subsequent test.

In the accompanying drawings, Figure 1 is a rear sectional elevation of a preferred type of apparatus involving the invention; Fig. 2 is a front sectional elevation of 40 a modified form of the invention; Fig. 3 is a corresponding view of a further modification; Fig. 4 is a sectional side elevation of the form shown in Fig. 3.

Referring to Fig. 1 of the drawings, the 45 numeral 1 indicates a box-like casing of brass or other suitable metal which is preferably permanently closed on all sides. Mounted in the lower part of the casing is an electro-magnet 2 with the poles of which 50 co-operates a spring armature 3 bent in the form of a right-angle, the base of which is mounted by suitable screws or the like upon a strip of insulation 4 attached to one side wall of the casing. Pivoted at 6 in the up-

per part of the casing is a swinging arm or lever 5 which is connected by a retractile spring 7 attached to a terminal stud 8 in the side wall of the casing, said spring being attached to the lever 5 by means of an adjustable set screw 12, whereby the tension 60 of the spring may be regulated. Intermediate the ends of the lever 5 there is mounted a pin or stud 8 which projects through an arc-shaped slot 10 in the front face of the casing, and on the outer end of said stud 65 there is secured a small knob 9. The lower end of the lever 5 is adapted to be engaged by an inclined nose piece on the end of the armature 3, as indicated, so that when the armature is in retracted position, the lever 70 5 will be held at one side of the vertical axis of the casing, against the tension of spring 7, but when the armature 3 is attracted by the magnet 2, the nose of said armature will pass out of engagement with the end of the lever 5 and permit said lever to be pulled over by the spring 7 to an inclined position 75 on the opposite side of the vertical axis of the casing, thereby moving the pin 8 in the slot 10 from one end to the other thereof 80 and until the lever engages a stationary stop 11 mounted on the inside of the front wall of the casing. The movement of the lever 5 under the action of the spring 7 causes the said lever to deliver a sharp blow against 85 the stop 11, thereby producing an audible signal in addition to the visual indication effected by the movement of the knob 9 across the slot.

In the form shown, the magnet 2 is differentially wound to respond to three different voltages, as for example, one and one-half, six and ten volts. For testing for the lower voltage, as for example, that developed by a single dry cell, the left-hand coil of 95 the magnet 2 is connected by wire 20 to an insulated stud 17 mounted in the bottom of the casing, said wire being connected at its other end to the cross connecting wire 21 between the spools. For the highest voltage, 100 the complete windings of both spools are connected in series with a central insulated terminal stud 16 by means of a wire 19, and for the intermediate voltage, a portion only of the winding of the right-hand magnet is 105 connected to an insulated stud 15 in the bottom of the casing by a wire 18, the fractional winding of the right-hand spool being con-

ected in series with the whole winding of the left-hand spool. Said left-hand spool is in turn connected by wire 22 with the armature 3.

5 In operating the device as described, to test a single cell, for example, to ascertain whether its voltage is sufficiently high to retain the cell in operation, contact is made between terminal stud 17 and one terminal 10 of the cell, and between the casing 1 and the other terminal of the cell, either by means of short sections of wire or by bringing the stud 17 and the casing 1 into direct contact with the battery terminals. 15 If the voltage of the cell is normal or higher than normal, the left-hand coil of magnet 2 will be energized and attract the armature 3, thereby releasing the lever 5 and permitting the same to be pulled over 20 against its stop 11, by a spring 7, and moving the stud 8 to the opposite end of the slot 10, giving both a visual and audible indication that the voltage of the cell is normal. If the voltage of the cell is below normal, 25 the current flowing through the coil of magnet 2 is insufficient to attract the armature and no indication is given, but the armature remains in retracted position, locking the lever 5 against movement. The complete circuit effecting the operation aforesaid is as follows: From one terminal of the cell to be tested through insulated contact stud 17, wires 20 and 21, the left-hand coil of magnet 2, wire 22, armature 3, lever 5 to 30 the metallic casing 1 back to the other terminal of the cell which is in electrical contact with said casing. Immediately after the armature is retracted, the lever 5 moves out of engagement with the armature 3, 35 thereby breaking the circuit, so that practically none of the energy in the cell is wasted in the test. The apparatus may be immediately reset for a further test by moving the lever in the opposite direction, against 40 the tension of spring 7, by means of the knob 9 on the end of the stud 8 projecting through the slot 10 and until the lower end of the lever snaps behind the nose on the end of the armature 3. To test a battery or series of 45 cells for the intermediate voltage of six, the right hand stud 15 is connected with one terminal of the battery and the other terminal of the battery is electrically connected with the casing 1. The operation will be as before described, except that the current will flow from 50 the battery through terminal 15, conductor 18 through a portion of the right-hand coil of magnet 2, thence by conductor 21 through the entire left-hand coil of said magnet, 55 thence by conductor 22 to armature 3, lever 5, through the metallic casing 1 back to the battery. If the voltage of the battery tested is equal to or greater than the normal of six required, the magnet is energized sufficiently to attract its armature and the opera- 60

tion is as hereinbefore described, namely, the lever 5 is released and pulled over by its spring 7 and the circuit to the battery is broken between the armature 3 and the end of the lever 5. A similar operation takes place when the test of the maximum voltage of ten is desired, in which case, the intermediate stud 16 is connected through one terminal of the battery and the current flows by way of wire 19 through both coils of the magnet 2, wire 22, armature 3, lever 5, to the casing and thence back to the battery.

In the modified form of the device shown in Fig. 2, there is provided a casing 1^a similar to that shown in Fig. 1 having therein a solenoid provided with a winding calibrated to attract the central core of the solenoid when a current having the desired minimum voltage passes through the coil of the solenoid. The core of said solenoid consists of a magnetic section 3^a to which is attached a non-magnetic metallic section 3^b, of brass or the like, the upper end of which projects through an opening 10^a in the top of the casing. A spiral spring 7^a surrounding the upper end of the section 3^b tends to force the armature downward so that the upper end projects only a slight distance through the opening in the casing 1^a. The lower end of the armature 3^a is provided with a contact head 3^d above which is a groove or notch 3^c. The contact head 3^d is adapted to normally engage the forked end of insulated contact stud 6^a mounted in the bottom of the casing. A leaf spring 5^a attached to the lower end of the solenoid is provided with a curved nose 5^b to snap into the groove 3^c on the lower end of the core, when the core is attracted and hold the core in its attracted position. One end of the coil of the solenoid is attached by wire 18^a to an insulated contact stud 8^a mounted at any convenient point on the casing 1^a. The other terminal of the coil of the solenoid is connected by a wire 22^a directly to the metallic casing 1^a. As shown, the device is designed to give an indication of a current of one specified minimum voltage only, but obviously by connecting the coil in sections to several terminal studs corresponding to 8^a, as in Fig. 1, the instrument may be calibrated to indicate other voltages, as will be understood. In operating this form of the apparatus, the armature core of the solenoid is pressed down by the finger until the lower end 3^d thereof engages the end of the contact stud 6^a and electrical connection is established between said stud and one terminal of the battery, and between stud 8^a and the other terminal of the battery or cell. The current will then flow from the battery through stud 6^a, solenoid core sections 3^a and 3^b to the casing, wire 22^a, through the coil of solenoid 2^a, thence by wire 18^a to insulated stud 8^a back to the battery. If the voltage 125

of the cell or battery tested is equal to that for which the instrument is calibrated, the pull of the solenoid coil 2^a is sufficient to retract core 3^a against the tension of spring 5^{7a} and draw the core up into the solenoid, thereby projecting the end of the section 3^b of the core through the hole in the upper part of the casing and causing the nose 5^b of spring 5^a to snap into the notch 3^c on the 10 end of the core and hold the core in its attracted position until it is forced down by the finger of the operator to its normal lower position. When the core 3^a is attracted or drawn up into the solenoid, the end 3^d thereof passes out of contact with the stud 6^a and breaks the circuit. If the cell tested does not develop the desired voltage, the current flowing through the coil of armature 2^a is not sufficient to attract the core and the 20 device gives no indication.

In the modification of the apparatus shown in Figs. 3 and 4, there is employed a metallic casing 1' generally like those heretofore explained, in which is mounted an 25 ordinary two-pole magnet 2' with the poles of which coöperates a bail-shaped armature 3' which is pivoted at 4' to the sides of the magnet. Between the coils of the magnet is located an indicator rod 5', the upper end of 30 which extends through a circular opening 10' in the top of the casing. Said rod is guided in suitable bracket pieces 7² supported by the magnet frame and is actuated by a helical spring 7' which tends to force 35 the end thereof out through the opening 10' when said rod is released. The rod 5' is held in its retracted position, against the tension of its spring 7', by means of a latch member 3'' rigidly attached to the middle 40 of the swinging armature 3' and coöperating with a notch in the lower end of the rod 7, as shown in Fig. 4. A leaf-spring 3''' attached to the casing 1' bears at one end on the armature 3' and forces the lower end of 45 the same toward the rod 5', so that the latch 3'' thereof will be in position to engage the notch in the rod 5' and hold said rod in its retracted position. One end of the windings of the magnet 2' is attached by a wire 18' to 50 insulated stud 6' carried by the casing and the other end of said winding is attached by a wire 22' directed to the casing. To operate this form of the apparatus, contact is made between the one terminal of the cell or 55 battery to be tested and insulated stud 6', and between the other terminal of the cell or battery and the casing 1'. The current then flows from the cell to stud 6', wire 18', coils of magnet 2', wire 22' to the casing, thence 60 back to the cell, the opposite terminal of which is in electrical contact with said casing. If the voltage of the cell or battery is equal to that for which the instrument is calibrated, the magnet 2' is energized and attracts its armature 3' against the tension of

spring 3''', thereby withdrawing the latch 3'' from engagement with the notch in the lower end of the rod 5', thereby releasing said rod and permitting the upper end of the same to be forced outward through the opening 10' in the top of the casing until the movement is arrested by the stop 5''. The projection of the end of the rod 5' and the sharp blow delivered by the stop 5'' on the casing will give both a visual and an audible 70 indication that the instrument has operated and that the voltage of the current tested is at least equal to that for which the instrument is calibrated. If the voltage is below normal, the instrument will not be operated but the rod 5' will remain locked in its retracted position. After the instrument has been operated, it is reset by forcing the rod downward against the tension of its spring until the lower end of said rod is engaged 75 by the latch on said armature and the instrument is ready for a further test. In this form of the apparatus, no means for breaking the circuit as soon as an indication has been obtained is provided, but obviously the 80 same means for effecting this object may be employed, as indicated in the modification shown in Fig. 2.

While the breaking of the circuit is a desirable object, it is not essential to the successful use of the apparatus and the instrument may be constructed and successfully applied without this structural and operative feature. The instruments are preferably constructed sufficiently small to be conveniently carried in the pocket or in a toolkit, and inasmuch as the internal mechanism is entirely protected by the closed casing, it is not liable to injury or derangement, even when carelessly used, but affords a simple, 90 reliable and efficient device that may be employed by careless or unskilled persons without danger either to the user or to the instrument.

What I claim is:—

1. A portable cell testing device, comprising a portable casing having an opening therein, an electro-magnet having a movable armature in said casing held against movement in all positions of the casing until actuated by the magnet, and a manually set indicating element associated with said armature and movable through said opening in the casing when the magnet is energized, said indicating element being operable, regardless of the position of the casing.

2. A portable cell testing device, comprising a portable casing having an opening therein, an electro-magnet having a movable armature in said casing held against movement in all positions of the casing until actuated by the magnet, a manually set indicating element in the casing movable through said opening when the magnet is energized, and means associated with the armature to

116

115

120

125

130

hold the indicating element in set relation, said indicating element being operable, regardless of the position of the casing.

3. A portable cell testing device, comprising a portable casing having an opening, a manually set indicating element in the casing movable through said opening, an electro-magnet in the casing controlling the indicating movement of said element, and means controlled by the magnet armature for breaking the circuit through the testing device when the indicating element operates, the magnet armature being held against movement in all positions of the casing until actuated by the magnet and the indicating element being operable, regardless of the position of the casing.

4. A portable cell testing device, comprising a portable casing having a slot therein, an arm in said casing having a stud moving in said slot, means for normally retracting said arm, and an electro-magnet in said casing having an armature normally restraining the movement of said arm and releasing said arm only upon energization of the magnet by passage of a current of requisite strength,

the said arm being operable to move to its retracted position when released, regardless of the position of the casing.

5. A portable cell testing device, comprising a portable casing having a slot therein, a pivoted arm in said casing having a stud moving in said slot, means for normally retracting said arm, an electro-magnet in said casing having an armature normally restraining the movement of said arm and releasing said arm only upon energization of the magnet by the passage of the current of requisite strength, and a circuit for said magnet including terminal connections and the armature and arm aforesaid, which circuit is broken by the disengagement of the armature and arm, the said arm being operable to move to its retracted position when released, regardless of the position of the casing.

In testimony whereof I affix my signature, in presence of two witnesses.

JOSEPH O. LUTHY.
